HYPODERMIC SYRINGE

Marvin A. Blake, Dallas, Tex., assignor to American Instrument Corporation, a corporation of Texas

Application February 16, 1948, Serial No. 8,719

3 Claims. (Cl. 128—218)

1

This invention relates to hypodermic syringes and more particularly to a syringe in which provision is made for predetermining medicinal dosages to be administered.

The principal object of the invention is to accomplish in a simple and dependable manner that which has hitherto required a more or less complicated mechanism, that is to say, to provide a syringe equipped with a lever disposed in convenient relation to the conventional finger grips by which the syringe barrel is held, so that the said lever may be manipulated from side to side as the plunger is depressed, thereby controlling the latter's movement to correspondingly predetermine the quantity of fluid ejected from the syringe barrel. The lever is effective to accomplish the foregoing through the provision of a plurality of columns of notches in the plunger, the notches of one column being staggered in relation to the notches of another column, said notches receiving a spring pressed detent retained in a disc-like member rotatably embracing the non-rotatable plunger and actuated by said lever to change the position of the detent with respect to notches of alternate columns, thus to permit displacement of the plunger a distance equal to the spaces between the notches.

Another object of the invention is to provide a dosage predetermining means for hypodermic syringes of such design and construction that accidental overdosage is not possible and further, the control mechanism can be employed equally as well in darkness as in light. Moreover, when not needed, the mechanism may be quickly rendered inoperative to convert the syringe to conventional use.

Still another object of the invention is to provide a dosage control mechanism for hypodermic syringes which will in no wise interfere with filling the barrel and evacuating air therefrom, this being done with the mechanism in neutral position, allowing free and unrestricted movement of the plunger.

With the foregoing and other objects in view, the invention has further reference to certain features of accomplishment which will become apparent as the description proceeds, taken in connection with the accompanying drawing wherein:

Figure 1 is a side elevational view of a hypodermic syringe constructed according to the invention.

Figure 2 is a side elevational view showing per se a modified form of plunger which is inter-

2

changeable with a plunger having a more or less number of notches therein.

Figure 3 is a view of the syringe shown in Figure 1 in vertical section, and

5 Figure 4 is a view in transverse section on a larger scale, taken on line 4—4 of Figure 3. Continuing with a more detailed description of the drawing, reference numeral 10 denotes a cylindrical shell adapted to enclose and protect the 10 glass ampule or barrel 11 of the syringe, into which is drawn the desired medicinal fluid through a conventional hypodermic needle not shown, attached to the inlet 12 of the syringe. Openings 13 in the shell 10 provide visibility to 15 determine the amount of fluid in the barrel.

Slidable in the barrel 11 is a piston 14 which is actuated by a plunger rod 15, encased in a plunger tube 16. The plunger elements are assembled by first placing the rubber washers of the 20 piston 14 on the rod 15 so that they will rest on the disc 17 affixed to the end of the rod. The tube 16 is then slid onto the rod so that its lower end will bear against the uppermost of the piston washers. Finally a knob 18 is threaded onto the 25 upper end of the rod 15.

The upper end of the shell 10 is exteriorly threaded to receive first, a knurled ring 19, followed by a transverse finger grip 20 and finally, a cap 21.

30 Within the shell 10 at its bottom is disposed a sealing washer 22 against which bears the lower end of the barrel 11. The upper end of the barrel is sealed by a rubber washer 23 which is held in place by pressure of the cap 21 bearing against 35 the dosage control mechanism enclosed in the cap and to which further reference will be made presently in detail.

It will be observed that the tube 16 has a longitudinal flat 24 on one side thereof which corresponds to a flat segment of the aperture in the cap 21 through which the plunger reciprocates. This arrangement insures that the plunger will be constrained against other than reciprocative displacement with respect to the syringe body. The 45 flattened portion 24 of the tube possesses the other characteristic of providing a neutral position for the dosage control mechanism, to become apparent presently.

Centered approximately 120° apart on the 50 plunger tube 16 are two columns or longitudinal rows of recesses or notches 25. The relative spacing between the notches of one row and those of the companion row determines the quantity of fluid which will be ejected by the piston 14 from the barrel 11, such spacing being predetermined

according to the cubic inch capacity of the barrel.

To control the effective displacement of the plunger, a disc 26 is arranged in the cap 21 and is centrally apertured to receive the plunger, provision being made to accommodate the flat 24 of the tube 16 so that the plunger will not rotate in the disc. An annular groove 27 is made in the periphery of the disc 26 and disposed in this groove is a spring ring 28, the ends thereof being anchored in recesses 29, as shown in Figure 4, yet allowing for limited expansion of the spring. A semi-circular element 29 lies within the confines of the spring ring 28 in a recess made in the disc 26 opposite the anchorage of the spring. The flat area of the element is adapted to bear, under tension of the spring 28, against the surface of the plunger which latter includes the tube 16 containing the notches 25. Since only the disc 26 is rotatable in relation to the plunger and syringe body, the element 29 may change position with respect to the two columns of notches 25 only by oscillating the disc 26. This is accomplished by the knob or lever 30 whose stem is connected to the periphery of the disc 26 and protrudes through a slot 31 in the wall of the cap.

As the disc 26 is rotated, the element 29 rides out of a retaining notch 25 onto the common surface of the plunger against the constricting action of the spring 28 and is disposed between opposing notches 25 of the companion row of notches. Thumb pressure on the knob 18 will depress the plunger until the next succeeding notch 25 is brought into a position to receive the element 29. Thus, the degree of travel of the plunger the distance equal to half the distance between the notches of one row determines the quantity of fluid ejected from the syringe by the piston 14. Should it be desired to administer an equal dosage, the control lever 30 is shifted to the opposite extreme and the plunger further depressed. By counting the number of times the lever 30 is moved from side to side, the user is apprised of the quantity of medicine administered of even larger doses.

The slot 31 in which the lever 30 is oscillated has a recess 32 at each end thereof and a recess 33 midway between its ends. The end recesses 32 prevent too free movement of the lever 30 from extreme positions thereof and serve to indicate to the user the position of the disc. The intermediate notch 33 is adapted to retain the element 29 in register with the longitudinal flattened portion 24 of the plunger or in neutral position. When so disposed, the element will not interfere with free and unrestricted movement of the plunger such as when refilling the barrel 11 or in cases when the dosage constitutes the entire contents of the syringe.

In Figure 2 is shown a plunger in which the notches of each row are spaced more closely than in Figures 1 and 3. It is a simple matter to substitute plungers or the notched sleeves 16 when changes in quantity of medicine to be administered are indicated.

Manifestly, the construction as shown and described is capable of some modification and such modification as may be construed to fall within the scope and meaning of the appended claims is also considered to be within the spirit and intent of the invention.

What is claimed is:

1. A hypodermic syringe including a barrel and a plunger having an interchangeable sleeve thereon, the latter having a longitudinal flattened portion and two parallel and longitudinal rows of notches therein, the notches of one row being staggered in relation to the notches of the companion row, a cap on said barrel apertured to conformably receive said plunger sleeve to hold said plunger against other than reciprocative movement with respect to said barrel, a disc rotatable in said cap, a spring retained element in said disc, means for oscillating said disc to alternately align said element with the notches of said rows to thereby limit the degree of longitudinal displacement of said plunger and means for retarding movement of said latter means at each extreme position and, at an intermediate position, for aligning said element with the flattened portion of said sleeve to release said plunger for unrestricted longitudinal displacement.

2. A hypodermic syringe including a barrel and a plunger, an interchangeable sleeve on said plunger having staggered notches arranged longitudinally therein and held with said plunger against rotative displacement with respect to said barrel, a disc rotatably mounted on said plunger through which the latter is adapted to reciprocate, a cap enclosing said disc and having a slot therein, a spring pressed element in said disc, a control lever attached to said disc and extending through the slot of said cap for oscillating the disc to dispose said element in alternate alignment with said notches to limit longitudinal displacement of said plunger and means for releasing said plunger for unrestricted longitudinal movement.

3. In a hypodermic syringe, a barrel and plunger, a sleeve on said plunger having longitudinally staggered notches therein, means for holding said sleeve and plunger against other than longitudinal displacement with respect to said barrel, a cap non-rotatably mounted on the plunger having a slot in one side thereof, a centrally apertured disc rotatable in said cap having a peripheral groove, an element in said disc and a spring lying in said groove to bear against and urge said element toward the aperture of said disc and against the sleeve of said plunger slidable in said aperture for alternate alignment with said notches to limit longitudinal displacement of said plunger and to predetermine the quantity of fluid expelled from said barrel.
